By *A. Murphy Jr.* Attorney.

UNITED STATES PATENT OFFICE.

LLOYD N. HOST, OF GRAND RAPIDS, MICHIGAN.

RECORD-PLACER.

1,349,611.

Specification of Letters Patent. Patented Aug. 17, 1920.

Application filed May 7, 1919. Serial No. 295,255.

To all whom it may concern:

Be it known that I, LLOYD N. Host, a citizen of the United States, residing at Grand Rapids, in the county of Kent and State of Michigan, have invented certain new and useful Improvements in Record-Placers; and I do hereby declare the following to be a full, clear, and exact description of the invention, such as will enable others skilled in the art to which it appertains to make and use the same.

My invention relates to improvements in record placers for talking machines.

An important object of this invention is to provide a record placer for talking machines having means for expeditiously alining the opening in the disk with the pin carried by the turn-table.

A further object of this invention is to provide a record placer for talking machines which may be stamped from a single piece of metal and which may thereby be produced at a very small cost.

A further object of this invention is to provide a record placer which may be readily attached to a talking machine or removed therefrom.

Other objects and advantages of the invention will be apparent during the course of the following description.

In the accompanying drawing forming a part of this application and in which like numerals are employed to designate like parts throughout the same,

35 Figure 1 is a perspective of a record placer embodied in my invention,

Fig. 2 is a transverse view through a talking machine turn-table and a record, showing the record placer in use,

40 Fig. 3 is a plan view of the turn-table and record, showing a slightly modified form of the invention applied, and

Fig. 4 is a fragmentary end elevation of the turn table and record placer, the view 45 showing the manner of applying the record.

In the drawings, wherein for the purpose of illustration is shown the preferred embodiments of my invention, the numeral 5 designates the turn-table of a talking machine and is mounted on a drive shaft 6. The turn-table is provided with a central upstanding pin 7 adapted to be received within an opening 8 in a disk 9. As illustrated in Figs. 1 and 2, I have pro-

vided a record placer designated generally 55 by the numeral 10. The record placer is adapted to be arranged between the disk and the turn-table and is therefore of a very thin metal. The record placer includes a plate having a radial arm 10' having an 60 opening 11 therein adapted to receive the pin 7 of the turn-table. The forward end portion of the arm 10' is provided with outwardly diverging arms 12 extending to the periphery of the record 9. The outer ends 65 of the arms 12 are provided with upstanding shoulders 13 adapted to be engaged by the periphery of the disk 9. In the form of my invention illustrated in Figs. 1 and 2, the shoulders 13 which are curved in the 70 arc of a circle having the pin 7 as a center, and form a stop are extended above the upper surface of the disk 9 to insure placing of the record in its proper position on the turn-table and to bring the opening 8 in 75 direct alinement with the pin 7. The arms 12 extend outwardly at acute angles.

In the form of my invention illustrated in Fig. 3, the record placer has its arms 14 extending outwardly at a lesser angle than 80 80 is shown in Figs. 1 and 2. The shoulders 15 of the construction shown in Fig. 3 terminate flush with the top of the record.

In the use of my invention, the record placer is first placed upon the turn-table as 85 indicated in Fig. 2. In placing a disk on the turn-table, its periphery is first engaged with the shoulders of the placer. The engagement of the periphery of the disk with the shoulders of the placer insures alinement 90 of the opening in the disk with the pin carried by the turn-table.

While I have shown and described the preferred embodiments of my invention it is understood that I may make such minor 95 changes in arrangement and construction of parts as will remain within the spirit of the invention and the scope of the appended claims.

Having thus described my invention, what 100 I claim is:—

1. A disk record placer for phonographs including, an arm adapted to be mounted radially on the turn-table of a talking machine, outwardly diverging arms secured to 105 said first named arm and extending to the periphery of a record, and upwardly extending shoulders carried by said outwardly di-

verging arms adapted to be engaged by the periphery of a record to dispose the record in a position where the opening therein will be in alinement with the pin of the turn table.

2. A disk record placer for talking machines including, a radial arm having means for mounting the same on a turn-table of a talking machine, a pair of arms diverging outwardly at an acute angle from said first named arm, and upstanding shoulders secured to said outwardly diverging arms and adapted to be engaged by the periphery of a record to prevent the record from moving edgewise when mounting the record on the turn table.

3. A disk record placer including a plurality of radially disposed arms, all of which being connected together at a common point at one end, means for mounting the arms on a turn table of a talking machine with the free ends thereof disposed outwardly, and upstanding lugs carried by the free ends of the arms against which the edge of a disk record is adapted to rest and serving as a fulcrum for the record in placing the same in position on the turn table and to cause

the record to be engaged at its center by the upstanding pin of the turn table.

4. In combination, the turn-table of a talking machine and a disk record, a disk centering pin carried by the turn table, a plate held upon the turn-table by the pin, and means carried by the plate and curved on the arc of a circle having the pin as a center so as to position the eye of the disk in alinement with the pin when the head of the pin is in engagement with the stop.

5. The combination with a turn-table of a talking machine provided with an up-standing centering pin and a disk record, of upstanding stops carried by the turn-table and curved to conform to the edge of the record and adapted to engage the record to retain the same in such position where the eye thereof will be in alinement with the upstanding pin.

In testimony whereof I affix my signature in presence of two witnesses.

LLOYD N. HOST.
